Primary Examiner — Ruth McInroy(74) *Attorney, Agent, or Firm* — Locke Lord Bissell & Liddell LLP(57) **CLAIM**

We claim the ornamental design for a combined wet/dry vacuum cleaner with onboard tool storage and integrated dustpan accessory, as shown and described.

DESCRIPTION

FIG. 1 is a front perspective view of a combined wet/dry vacuum cleaner with onboard tool storage and integrated dustpan accessory showing our new design;

FIG. 2 is a front elevational view thereof;

FIG. 3 is a rear elevational view thereof;

FIG. 4 is a side thereof;

FIG. 5 is a side view showing the side opposite that shown in FIG. 4;

FIG. 6 is a top view thereof; and,

FIG. 7 is a bottom view thereof.

The broken lines in the Figures are for the purpose of illustrating exemplary environmental structure and forms no part of the claimed design.
